UNITED STATES PATENT OFFICE.

LOUIS K. TERRY, OF COOKS, NEW MEXICO.

HANGER FOR MINERS' LAMPS.

1,082,779.

Specification of Letters Patent.

Patented Dec. 30, 1913.

Application filed August 7, 1913. Serial No. 733,449.

To all whom it may concern:

Be it known that I, LOUIS K. TERRY, a citizen of the United States, residing at Cooks, in the county of Luna and State of New Mexico, have invented certain new and useful Improvements in Hangers for Miners' Lamps, of which the following is a specification.

My invention relates to a new and useful hanger for miners' lamps, and its object is to provide a device especially intended for the use of miners which device will be formed with a hook by which it may be conveniently engaged upon a protuberance or irregularity in the wall of a shaft or tunnel, and which will also carry a portion so shaped as to adapt it to contain a miner's lamp.

A still further object of the invention is to provide a device of the character described that will be strong, durable, simple and efficient and comparatively inexpensive to produce, also one in which the several parts will not be likely to get out of order.

With the above and other objects in view, the invention has relation to certain novel features of construction, an example of which is described in the following specification and illustrated in the accompanying drawing, wherein:

Figure 1 is a front view of my hanger for miners' lamps. Fig. 2 is a top view of the same. Fig. 3 is a front view showing a slightly modified form of the invention. Fig. 4 is a side view of the modification. Fig. 5 is a transverse sectional view of the same, the section being taken upon the line X—X of Fig. 3.

Referring now more particularly to the drawing, wherein like reference characters designate similar parts in all the figures, the numeral 1 denotes the body of my device which consists of an elongated metal bar terminating at its upper extremity in a pointed hook as indicated at 2, and bent forwardly at its lower end as indicated at 3. Adjacent to the lower extremity of the member 1 there is mounted upon said member an arcuate bracket 4 extending through an arc somewhat greater than a semi-circle. The diameter of the bracket 4 will be such

that the body portions of a standard miner's lamp may be securely engaged within said bracket. Opposite to the bracket 4 there is mounted upon the rear face of the member 1 a cross-piece 5 the extremities of which are curved rearwardly. When the hook 2 is made to engage some irregularity in the wall of a shaft or tunnel, the extremities of the cross-piece 5 will rest against the wall beneath the point at which the hook is supported and will thus tend to hold steady the lamp (not shown) held by the bracket 4. Above the members 4 and 5, enlarged portions are formed oppositely upon the edges of said bar, which portions are curved rearwardly to a tubular form as indicated at 6. The members 6 respectively serve as sockets receiving vertical portions of two handle-forming links 7, which handles will be swung to an adjacent position to the rear of the bar 1 when the hanger is manually supported. The forwardly bent lower end of the bar 1 forms a support for the lamp which is to be engaged by the bracket 4.

The modified construction of my invention illustrated in Figs. 3, 4 and 5 of the drawing, differs from the construction already described in that the handles 7 are omitted from the device in the modification.

The invention is presented as including all such modifications and changes as properly come within the scope of the following claims:

What I claim is:

1. A hanger for miners' lamps comprising a bar formed with a hook at its upper extremity and having its lower extremity bent at a right angle in an opposite direction from said hook, an arcuate bracket mounted fast upon the lower portion of said bar above the out-turned extremity thereof, a cross-arm mounted upon the lower portion of the bar transversely thereof having its extremities curved slightly in a direction opposite from the curvature existing in said bracket.

2. A hanger for miners' lamps comprising a vertical bar formed at its upper extremity with a rearwardly projecting hook and having its lower end forwardly bent at a right angle, an arcuate bracket rigidly mounted

upon the lower portion of said bar and extending forwardly therefrom, a cross-piece mounted transversely upon the bar at the rear of said bracket having its extremities 5 turned rearwardly, and a pair of handle members mounted upon the bar above said bracket and cross-piece.

In testimony whereof I have signed my name to this specification in the presence of two subscribing witnesses.

LOUIS K. TERRY.
